A. A. ROSS,
COTTON PICKER.

APPLICATION FILED MAR. 13, 1918. RENEWED FEB. 5, 1919.

1,314,096.

Patented Aug. 26, 1919.

UNITED STATES PATENT OFFICE.

AMOS A. ROSS, OF HASKELL, OKLAHOMA.

COTTON-PICKER.

1,314,096.

Specification of Letters Patent. Patented Aug. 26, 1919.

Application filed March 13, 1918. Serial No. 222,136. Renewed February 5, 1919. Serial No. 275,249.

To all whom it may concern:

Be it known that I, AMOS A. ROSS, a citizen of the United States, residing at Haskell, in the county of Muskogee and State 5 of Oklahoma, have invented certain new and useful Improvements in Cotton-Pickers; and I do hereby declare the following to be a full, clear, and exact description of the invention, such as will enable others skilled in the art to which it appertains to 10 make and use the same.

This invention relates to manual cotton pickers, and has for its principal object to provide a device of this character which is 15 cheap and inexpensive and one which, when applied to the hand, can be conveniently and effectively used to pick cotton in a more easy and expeditious manner.

A further object of the invention is to 20 provide a plurality of finger pieces, certain of which are formed with suitable prongs or burs, whereby when the finger pieces are operatively attached to the fingers and thumb of the hand, they can be effectively 25 used to pick the cotton bolls from the pods under varying conditions.

A further object of the invention is to provide a plurality of finger pieces, each of which embodies a pair of adjustably 30 connected plates, one of which latter is provided with suitable prongs or burs, the position of said plates being adapted to be interchanged on the ends of the fingers to enable them to be separately used for picking cotton under varying conditions due to 35 the climatic changes in the cotton season.

A still further object of the invention is to provide finger pieces, each embodying a pair of plates which are adjustably and 40 yieldingly connected, whereby they may be quickly and conveniently attached to the ends of the fingers.

With these and other objects in view as will appear as the description proceeds, the 45 invention comprises the various novel features of construction, combination and arrangement of parts as will be more fully described hereinafter and afterward specifically claimed.

50 Referring to the drawings,

Figure 1 represents a front elevation of the cotton picker operatively attached to the hand.

Fig. 2 represents a plan view of the hand strap. 55

Fig. 3 represents a plan view of one of the finger pieces.

Fig. 4 represents an enlarged transverse sectional view taken on a plane indicated by the line 4—4 on Fig. 3. 60

Fig. 5 represents a plan view of the thumb piece, and

Fig. 6 represents a transverse sectional view taken on a plane indicated by the line 6—6 on Fig. 5. 65

In order that the construction and operation of the invention may be readily comprehended by those skilled in the art to which the invention relates, I have illustrated an approved embodiment thereof in 70 the accompanying drawings and will now proceed to fully describe the same, in connection with said drawings, in which 1 is a hand strap, one end of which is slightly enlarged in width and provided with a 75 thumb opening 2, as clearly shown in Fig. 2. The opposite end of the strap terminates in a wrist strap 3 which may be either formed integrally with the hand strap 1 or may be made of a separate piece and 80 connected thereto. 4 indicates a buckle attached to the hand strap adjacent one side edge and at a point adjacent to the thumb opening 2. The hand strap is also provided with a pair of slots 5 adjacent the buckle 85 4 and are adapted to receive the wrist strap 3 in attaching the hand strap to the hand.

In attaching the strap 1, the thumb is inserted through the opening 2 and the strap extended across the back of the hand under 90 and over the palm in front of the thumb and thence across the back, through the slots 5 and then around the wrist and adjustably connected to the buckle 4.

6 is a thumb piece and comprises a plate 95 7, the forward end of which is somewhat pointed as indicated by the numeral 8. This plate, as shown in Fig. 6, is curved transversely to fit the thumb and is provided adjacent its forward end with prongs 9 100 which are stamped up from the plate. These prongs may be set at an angle with respect to the plate to enable them to be used in the most efficient manner. A pair of spaced slots 10 are formed in each side 105 of the plate 7 and have connected therein

thumb straps 11. These straps are preferably formed of elastic material, but it is of course to be understood that they may be formed of either metal, leather, or other material found most desirable.

5 An attaching strap 12 has one end secured to the thumb straps 11, while its opposite end is provided with buttonholes 13, whereby it may be adjustably connected to the 10 button 14 of the hand strap 1, and thus serve to prevent the thumb piece from being disengaged from the thumb during the picking operation.

Each of the fingers of the hand are provided 15 with finger pieces 15, and each comprises transversely curved plates 16 and 17. These plates are pointed at their forward ends and one of them is stamped up to provide burs or prongs 18. In this instance, 20 the plate 16 is provided with a pair of prongs, while the plate 17 is simply smooth for the following reason. It is a well known fact that it is much more difficult to extract or pick the cotton boll from the pod after 25 a frost than it is before, and for this reason I have provided the differently constructed plates 16 and 17. Just after a frost, when the cotton is difficult to pluck from the pod, the plate 16 carrying the prongs or burs is 30 utilized, and when it is desired to use the picker before a frost, the plates are interchanged in position so that the plate 17 can be effectively used in picking the cotton. The plates 17 are each provided adjacent their 35 tip with an aperture 17a whereby they may be attached to the fingers of a glove that may be worn to protect the hand, said connection holding the plates in operative position.

40 It is to be further noted that the plates 16 and 17 are connected by a finger strap which is extended through slots 20 in the opposite side edges of the plates 16 and 17. This strap in this instance is formed of 45 elastic material so that the plates may be adjustably positioned on fingers of various sizes. It is, if course, to be understood that this finger strap 19 can also be made of metal, leather or other material and if desirable 50 provided with a suitable adjustment, whereby it can be attached securely and readily to the fingers.

By constructing the finger pieces of plates which are of width substantially equal to 55 that of the fingers and thumb and attaching them thereto by thin straps, it will be

apparent that the finger pieces will rest more comfortably on the fingers and will permit of a greater freedom and ease of movement of the fingers than could be had if the finger pieces were made of a metal ferrule or thimble. It is also to be noted 60 that the finger pieces will protect the fingers from injury by the sharp points of the cotton pods while picking the cotton. On cold 65 and frosty mornings, when the cold affects the fingers thus retarding the picking of cotton in an expeditious manner, these finger pieces will offer a great deal of protection to the fingers and render the picking 70 easier.

From the foregoing description, taken in connection with the accompanying drawings, it is to be understood that while I have illustrated the principle of operation of the 75 invention, together with the best embodiment thereof, I desire to have it understood that such changes in the construction and arrangement of parts may be made when desired as are within the scope of the ap- 80 pended claims.

Having thus described my invention, what I claim as new is:—

1. In a manual cotton picker of the class described, a finger piece comprising a pair 85 of transversely curved plates, burs stamped up from one of said plates, and a finger strap for connecting said plates.

2. In a manual cotton picker of the class described, a finger piece comprising a pair 90 of plates, burs stamped up from one of said plates, and an elastic finger strap connecting the opposite side edges of said plates.

3. In a manual cotton picker of the class 95 described, a finger piece comprising a pair of plates, each having one end pointed and oppositely arranged with respect to each other, burs stamped up from one of said plates adjacent its pointed end, and a finger 100 strap adjustably connecting said plates, said plates adapted to be reversed and interchanged in operative position on the end of the finger.

In testimony whereof I have signed my 105 name to this specification in the presence of two subscribing witnesses.

AMOS A. ROSS.
